LIQUID MIXING DEVICE

Charles I. Sayles, Ithaca, N. Y., assignor to Vera
David, New York, N. Y.

Application November 8, 1938, Serial No. 239,484

7 Claims. (Cl. 210—28)

This invention relates to liquid mixing devices and more especially to a device for adding a reagent such, for example, as chlorine solution in predetermined ratio to a flowing stream of liquid such, for example, as water.

An object of this invention is a liquid feeding device of the character referred to which is of extremely simple construction, inexpensive to manufacture, has no moving parts and in which the feeding of the reagent is visible.

In a preferred embodiment of the invention, there is provided a chamber open at its bottom, together with means for confining a body of liquid around said chamber up to a predetermined height above the bottom of the chamber, means for supplying liquid such, for example, as water to said confining means at a constant rate, and means to withdraw liquid from said confining means at a constant rate greater than said supply rate. The last-named means communicates with the stream of liquid such, for example, as water to which reagent is to be added. Means also are provided for supplying reagent to said chamber at a constant pressure not greater than the liquid pressure at the bottom of said chamber when the liquid in said confining means is at said predetermined height. At such time as liquid is not being withdrawn from said confining means, air pressure in said chamber balances or exceeds the supply pressure of the reagent so that there is no flow of reagent to said chamber. However, upon withdrawal of liquid from said confining means, the air pressure in said chamber decreases below the supply pressure of the reagent so that reagent flows into said chamber and from said chamber into the stream of water to be treated. Upon cessation of withdrawal, the original liquid depth is restored, thereupon preventing further flowing of reagent to said chamber.

As will be apparent from the above description, the device is simple in structure, inexpensive to manufacture and has no moving parts. Furthermore, it is applicable to all the sizes of installations, is easily manipulated, has no complicated connections and has no parts under excessive pressure requiring tight joints. In addition, it is easily adapted to any rate of water flow, is nonclogging and easily cleaned and also the feeding of the reagent may be made visible by constructing such device in part of glass or other similar transparent material.

Other objects, novel features and advantages of this invention will become apparent from the following specification and accompanying drawings, wherein:

Fig. 1 is a vertical section through an embodiment of the invention, and

Fig. 2 illustrates diagrammatically the manner of connecting the device to the water system of a building.

The hollow base member 10 of the device preferably is cylindrical and is formed of any suitable material such, for example, as ceramic material. Within the base member is provided a small platform 11 having a recess in which is received the bottom rim of a vertical tube 12, there being a liquid tight seal between the bottom of the tube and the platform. A pipe 13 passes through the vertical wall of the base member 10 and has its inner end turned downwardly into the tubular member 12. A passageway 14 in the platform 11 leads from the bottom of the tank or confining means formed by the tubular member 12 and communicates with a pipe 15.

An air-tight reservoir 16 composed of suitable material such, for example, as ceramic material or glass rests on the upper edge of the base member 10. A tubular member 17 has its upper end fitting into a groove in the bottom of the reservoir 16, there being a fluidtight connection 25 between the tubular member and the reservoir and said tubular member 17 projects downwardly into the tubular member 12 which is slightly larger in diameter than the tubular member 17. In the bottom of the reservoir 16 is provided a passageway 18 with which communicates a conduit 19 extending into the chamber formed by the tubular member 17, the conduit 19 having a return bend. A valve 20 is provided for controlling flow of reagent through the passageway 18. A tube 21 extends through the top of the reservoir 16 to a predetermined distance above the exposed end of the conduit 19 and at its upper end is open to atmosphere.

A pipe 22 leads from the bottom of the bottom member 10 and in the vertical wall of the bottom member 10 is provided a transparent window 23 through which the interior of the member 10 may be viewed. Also, in the vertical wall of the bottom member 10 is provided an air vent 29.

The tube 21 is so arranged that the hydraulic head h_1 between the bottom thereof and the outlet end of the conduit 19 within the tubular member 17 is either exactly equal to or slightly less than the hydraulic head h_2 between the top rim of the tubular member 12 and the bottom rim of the tubular member 17. Thus, when the tubular member 12 is full of liquid, the air pressure in the tubular member 17 equal or exceeds the pressure tending to cause reagent to flow from 55

the reservoir 16 through the conduit 19 with the result that under such circumstances, flow is prevented. However, upon decrease of liquid level in the tubular member 12, the air pressure within the tubular member 17 drops sufficiently to permit the flow of reagent through the conduit 19 into the tubular member 17.

As shown in Fig. 2, the pipe 15 communicates with the inlet for the pump 25 by which water is pumped from a suitable supply such, for example, as a lake or well through the pipe 26 to the water system of a building. The pipe 13 previously mentioned leads from the pipe 26 and is provided with a valve 27 by means of which the rate of flow through the pipe 13 may be controlled.

When the pump 25 is at rest, the confining means 12 is filled to overflowing by water supplied thereto through the pipe 13, the overflow flowing out through the pipe 22 and being carried away by any suitable arrangement. The air pressure in the chamber defined by the tubular member 17 is sufficiently high to prevent the flow of reagent through the conduit 19. When the pump starts operating, liquid is withdrawn from the confining means 12 through the pipe 15 at a greater rate than water is supplied thereto through the pipe 13. As a result, the liquid is completely withdrawn from the confining means, thus reducing the back pressure and permitting the flow of reagent through the conduit 19 at a rate determined by the setting of the valve 20. The reagent, mixed with the water supplied through the pipe 13, is carried by the pipe 15 into the stream of water drawn by the pump 25 and supplied to the water system. Upon cessation of operation of the pump 25, the confining means 12 is again filled with water to overflowing, thereupon stopping the flow of reagent through the conduit 19. The return bend at the end of the tube 19 insures the application of pressure within the tubular member 17 to the reagent contained in the tank 16 for the purpose of stopping the flow of the reagent. Unless the tube 19 were provided with such return bend, the surface tension of the liquid would be inadequate to transmit the pressure to the liquid in the tank 16 and instead bubbles or air enclosed in the chamber 17 would rise through the tube 19, pass through the valve 18 and flow through the liquid in the tank 16 while liquid reagent would continue to flow through the tube 19 as the air bubbled back therethrough.

The apparatus herein disclosed has the advantage of simplicity of structure, low manufacturing cost and absence of moving parts. Also, the various parts may be composed of any suitable material and where the parts are composed of glass or other transparent material, the feed of reagent is clearly visible. Furthermore, where the bottom member is made of opaque material, the window 23 permits visible observation of the feed of the reagent.

It is of course understood that various modifications may be made in the structure above described, without in any way departing from the spirit of the invention as defined in the appended claims. It is further to be understood that the apparatus above described is suitable for use in mixing any two liquids and that chlorine solutions in water have been cited herein merely as examples of such liquids.

I claim:

1. A device of the character described comprising a chamber open at its bottom, means to con-

fine a body of liquid around said chamber up to a predetermined height above the bottom of said chamber, means to supply liquid continuously to said confining means exterior of said chamber at a constant rate, means to withdraw liquid from the bottom of said confining means at a rate greater than said supply rate, and means to supply treating liquid by gravity to said chamber at a constant pressure not greater than the liquid pressure at the bottom of said chamber when the body of liquid surrounding said chamber is at said predetermined height.

2. A device of the character described comprising an open top tank, a hollow member arranged in said tank with its lower end open, means for supplying liquid to said tank exterior of said hollow member at constant rate, means to withdraw liquid from the bottom of said tank at a constant rate greater than said supply rate, and means to supply treating liquid by gravity to the upper part of said hollow member at a constant pressure not greater than the liquid pressure at the bottom of said hollow member when said tank is full of liquid.

3. A device of the character described comprising a first chamber open at its bottom, a second chamber open at its top and enclosing said first chamber, means for supplying liquid continuously to said second chamber exterior of said first chamber at constant rate, means to withdraw liquid from the bottom of said second chamber at a rate greater than said supply rate, and means to supply treating liquid by gravity to the upper part of said first chamber at a constant head not greater than the difference in head between the bottom of said first chamber and the top of said second chamber.

4. A device of the character described comprising a first chamber open at its bottom, a pipe extending into said first chamber and having its end portion extending upwardly, a second chamber open at its top and enclosing said first chamber, means to supply liquid continuously to said second chamber exterior of said first chamber at constant rate, means to withdraw liquid from the bottom of said second chamber at a rate greater than said supply rate, a supply of treating liquid at a higher elevation than the top of said first chamber communicating with said pipe, and means for maintaining the liquid head not greater than the difference in head between the bottom of said first chamber and the top of said second chamber.

5. A device of the character described comprising a first chamber open at its bottom, a pipe extending into said first chamber and having its end portion extending upwardly, a second chamber open at its top and enclosing said first chamber, means to supply liquid continuously to said second chamber exterior of said first chamber at constant rate, means to withdraw liquid from the bottom of said second chamber at a rate greater than said supply rate, a closed liquid reagent tank at a higher elevation than the top of said first chamber communicating with said pipe, and another pipe extending downwardly into said tank, the lower end of said last-named pipe being at an elevation above the end of said second pipe in said first chamber a distance not greater than the elevation of the top of said second chamber above the bottom of said first chamber and the upper end of said pipe extending through the wall of said tank into communication with atmosphere above the top wall of said tank.

6. A device of the character described comprising a first chamber open at its bottom, a second chamber open at its top and enclosing said first chamber, means to supply liquid continuously to said second chamber exterior of said first chamber at constant rate, means to withdraw liquid from the bottom of said second chamber at a rate greater than said supply rate, a closed reagent tank at a higher elevation than the top of said first chamber, a conduit leading from said reagent tank into the top of said first chamber, and a pipe extending downwardly into said tank, the lower end of said pipe being at an elevation above the end of said conduit in said first chamber a distance not greater than the elevation of the top of said second chamber above the bottom of said first chamber and the upper end of said pipe extending through the wall of said tank into communication with atmosphere above the top wall of said tank.

7. A device of the character described com-

prising a first tubular member open at its bottom and closed at its top, a second tubular member open at its top and closed at its bottom and surrounding said first tubular member, means to supply liquid continuously to said second tubular member at constant rate, means to withdraw liquid from the bottom of said second tubular member at a rate greater than said supply rate, a closed liquid reagent tank, a conduit leading from said tank and projecting into said first tubular member, and a pipe extending downwardly into said tank, the lower end of said last-named pipe being at an elevation above the end of said conduit in said first tubular member a distance not greater than the elevation of the top rim of said second tubular member above the bottom rim of said first tubular member and the upper end of said pipe extending through the wall of said tank into communication with atmosphere above the top wall of said tank.

CHARLES I. SAYLES.
